Inventor

UNITED STATES PATENT OFFICE.

EDWARD C. ROBERTS, OF SALTVILLE, VIRGINIA.

DRAWING-TABLE.

No. 919,245.

Specification of Letters Patent.

Patented April 20, 1909.

Application filed May 6, 1908. Serial No. 431,124.

To all whom it may concern:

Be it known that I, EDWARD C. ROBERTS, a citizen of the United States, resident of Saltville, in the county of Smyth and State 5 of Virginia, have made a certain new and useful Invention in Drawing-Tables; and I declare the following to be a full, clear, and exact description of the same, such as will enable others skilled in the art to which it applies to make and use the invention, reference being had to the accompanying drawings, and to characters of reference marked thereon, which form a part of this 10 specification.

Figure 1 is a section on the line 1—1, Fig. 2. Fig. 2 is a rear view of the table. Fig. 3 is a front view of the same. Fig. 4 is an end view of the same. Figs. 5, 6, and 7 are detail plan views of taps having glass insertions of different sizes. Fig. 8 is a section on the line 8—8, Fig. 9. Fig. 9 is a detail plan view of one of the fastening clips for the paper, as applied. Figs. 10 and 11 are detail views of one of the fastening studs for the 25 table top as applied.

This invention has relation to drawing tables, having for its object the provision of improved means whereby tracings may be readily made upon thicker paper than is 30 commonly used and with less injury or strain upon the eyes, and whereby pencil work may be more clearly seen.

With this object in view the invention consists in the novel construction and combinations of parts as hereinafter set forth:

In the accompanying drawings, illustrating the invention, the letter *a*, designates the table, which is composed of a top *b*, a bottom wall *c*, having an inclination of forty-five degrees to the horizontal and intersecting such top at the rear edge thereof, and a rear wall *d*, composed of two plane sections *d'*, *d''*, meeting at the vertical center of said rear wall and having an angular relation to each other. In 45 this manner a casing of general triangular prismatic form is provided, inasmuch as the sections of the rear wall are but slightly bowed out of line. The upper edges of the side walls of the table are provided with fastening studs or screws *e*, the heads of which are separated from the edge surfaces of the table by narrow intervals *e'*. The top *b*, of the table, which is removable, is provided with fastening plates *f*, provided with common key-hole shaped slots *f''*, which when fitted over the screws or studs *e*, and moved

slightly to one side will removably secure the top in position. This top is formed of a marginal frame of wood or other material having a transparent glass plate insertion, and the bottom wall *c*, and rear wall sections *d'*, *d''*, have mirror linings *c'*, and *d''d''*, respectively. A plurality of incandescent electric bulbs *g*, *g'*, are located at the intersection of the sections of said rear wall in a horizontal line, 65 suitable wiring being employed, as shown at *g'*. In this manner the rearward directed rays of light from the incandescent bulbs will be reflected forward by the inclined mirrored rear wall sections upon the mirror-lined bottom wall, which will reflect such light upward through the transparent glass plate insertion of the top wall. At the same time the forward directed rays of light from the bulbs will be reflected by the bottom wall mirror 70 through the transparent top wall plate.

In order that the table may have suitable support, a pedestal *h*, is provided located in the recess in front of and under the inclined bottom wall *c*, and having double vertical 80 hollow columns or standards *h'* wherein are received the vertically adjustable stems *i*, secured at their upper portions to the bottom wall of the table at *i'*. These stems are each provided with a series of rack teeth *j*, 85 which have engagement with the teeth of pinions *j'*, the shaft *j''*, of which has bearings in the column *h'*, and is provided with a central hand wheel *k*. Pawl devices *k'*, having engagement with the teeth of the pinions are 90 employed to fix the adjustment of the table. These pawl devices are pivoted to and carried by extensions *h''*, of the standards *h'*, *h''*.

For the purpose of accommodating tracings or drawings of varying sizes the top 95 wall or plate *b*, may be removed and a similar plate *b'*, or *b''*, having a smaller glass plate insertion substituted, a further object being to avoid passage of the reflected light except through the tracing or drawing itself.

A rear shelf extension *l*, is provided about on a line with the top *b*, for the reception of drawing instruments, and ventilators for the table are provided at *m*.

At each corner of the top *b*, a clip for fastening the paper is provided, as shown at *n*, such clip, which is composed of an oblong piece of flat metal, being secured at its outer end to the frame of the top by a screw *n'*, and having vertical spring movement to a slight degree upon such screw *n'*, in a recess *n''*, in the top frame, such movement being

controlled by an adjustment screw o , engaging the inner end portion of the clip and having a nut o' , at its lower end fitting closely within a similarly formed seat o^2 , of the top frame. The paper passes at the corner thereot over the rounded corner p , of the recess n^2 , (such corner being shown as provided with a short rounded metal or wire lining) and under the clip n , within the recess n^2 , below the same, adjustment of the screw o , being first made to raise the clip and admit the paper thereunder. Upon reverse adjustment of the screw o , the clip is lowered within the recess n^2 , to bear at its end or inner edge against the downturned corner portion q , of the paper, such corner portion being compressed between the inner end or edge of the clip and the end wall n^3 , of the recess n^2 , to fasten the paper securely, thus doing away with the use of thumb tacks or perforation or gluing of the paper.

Having described the invention, what I claim and desire to secure by Letters Patent is:

- 25 1. In a drawing table, the combination with a depending casing having a top wall provided with a transparent plate insertion, an inclined bottom wall provided with a mirror lining, and a rear wall provided with a mirror lining, said rear and bottom walls being joined to and substantially intersecting said top wall and each other, of an adjustable pedestal support located in front of and under the inclined bottom wall.
- 35 2. In a drawing table, the combination with a depending casing of general triangular prismatic form having a top wall provided with a transparent plate insertion, an inclined bottom wall provided with a mirror lining, and a rear wall provided with a mirror lining, of an adjustable pedestal support located in front of and under the inclined bottom wall and connected to said bottom wall.
- 45 3. In a drawing table, a depending casing of general triangular prismatic form having a top wall provided with a transparent plate insertion, an inclined bottom wall provided with a mirror lining, and a rear wall provided with a mirror lining and composed of two plane sections having an angular relation to each other.
- 55 4. In a drawing table, the combination with a casing having a top wall provided with a transparent plate insertion, an inclined bottom wall provided with a mirror lining, and a rear wall provided with a mirror lining and composed of two plane sections having an angular relation to each other, said rear and bottom walls being joined to and substantially intersecting said top wall and each other, of an adjustable pedestal support located in front of and under the inclined bottom wall.

5. In a drawing table, the combination with a casing having a top wall provided with a transparent plate insertion, an inclined bottom wall provided with a mirror lining, and a front wall provided with a mirror lining, said rear and bottom walls being joined to and substantially intersecting said top wall and each other, of a support having a hollow column, a stem having adjustment in said column and attached at the upper end thereof to the inclined bottom wall of the table, means for adjustment of said stem and table and means for fixing such adjustment.

6. In a drawing table, the combination with a casing having a top wall provided with a transparent plate insertion, an inclined bottom wall provided with a mirror lining, and a rear wall provided with a mirror lining, said rear and bottom walls being joined to and substantially intersecting said top wall and each other, of double hollow columns, stems having adjustment in said columns and attachment at the upper ends thereof to said inclined bottom wall of the table, said stems having rack teeth, a horizontal shaft having bearings carried by said columns, provided with pinions at the end portions thereof having engagement with the rack teeth of said stems, and a hand wheel, and means for fixing the adjustment of said stems and table.

7. In a drawing table, the combination of a casing having a removable top wall provided with a transparent plate insertion, an inclined bottom wall provided with a mirror lining, a rear wall provided with a mirror lining, said rear and bottom walls being joined to and substantially intersecting said top wall and each other, and vertically adjustable corner clamps for paper having each at its outer end portion a screw connection with said top wall and at its inner end portion an adjustment screw connection with said top wall, said top wall having corner recesses beneath said clamps to allow for adjustment thereof.

8. In a drawing table, the combination of a casing having a top wall provided with a transparent plate insertion, a bottom wall having an inclination of forty-five degrees and provided with a mirror lining, and a rear wall composed of two plane sections adapted for the insertion of lighting means between the same and having an angular relation to each other and a mirror lining, said rear and bottom walls being joined to and substantially intersecting said top wall and each other.

In testimony whereof I affix my signature, in presence of two witnesses.

EDWARD C. ROBERTS.
